UNITED STATES PATENT OFFICE

EDWARD JOHNSON, OF MONTCLAIR, NEW JERSEY, ASSIGNOR TO MEINECKE & COMPANY,
OF NEW YORK, N. Y., A CORPORATION OF NEW JERSEY

DESIGN FOR A TOILET BRUSH

Application filed September 16, 1932. Serial No. 44,869. Term of patent 14 years.

To all whom it may concern:

Be it known that I, EDWARD JOHNSON, a citizen of the United States, residing in Montclair, in the county of Essex and State of New Jersey, have invented a new, original, and ornamental Design for Toilet Brush, of which the following is a specification, reference being had to the accompanying drawing, forming part thereof, in which:—

The figure represents a perspective view of a toilet brush embodying this design.

I claim:

The ornamental design for a toilet brush as shown.

EDWARD JOHNSON.
